CLAIM

The ornamental design for a portion of track for track-laying vehicles as shown and described.

DESCRIPTION

1. Portion of track for track-laying vehicles
2. Portion of track for track-laying vehicles

1.1 : Top perspective view

1.2 : Bottom perspective view

1.3 : Top

1.4 : Right

1.5 : Left

1.6 : Front elevation view

1.7 : Rear elevation view

1.8 : Top perspective reference view

2.1 : Top perspective view

2.2 : Bottom perspective view

2.3 : Top

2.4 : Right

2.5 : Left

2.6 : Front elevation view

2.7 : Rear elevation view

2.8 : Top perspective reference view

1.1 is a top perspective view of a portion of a track for track-laying vehicles; 1.2 is a bottom perspective view thereof; 1.3 is a top view thereof; 1.4 is a right side view thereof; 1.5 is a left side view thereof; 1.6 is a front elevation thereof; 1.7 is a rear elevation thereof; 1.8 is a top perspective reference view thereof showing the state of use; 2.1 is a top perspective view of a portion of a track for track-laying vehicles; 2.2 is a bottom perspective view thereof; 2.3 is a top view thereof; 2.4 is a right side view thereof; 2.5 is a left side view thereof; 2.6 is a front elevation view thereof; 2.7 is a rear elevation view thereof; and 2.8 is a top perspective reference view thereof showing the state of use.
